UNITED STATES PATENT OFFICE.

FRANK R. BATCHELDER, OF WORCESTER, MASSACHUSETTS.

FABRIC POCKET.

1,074,685

Specification of Letters Patent.

Patented Oct. 7, 1913.

Application filed November 15, 1910. Serial No. 592,430.

To all whom it may concern:

Be it known that I, FRANK R. BATCHELDER, a citizen of the United States, residing at Worcester, in the county of Worcester 5 and State of Massachusetts, have invented new and useful Improvements in Fabric Pockets, of which the following is a specification.

This invention relates to improvements in fabric pockets intended to carry heavy or sharp-pointed objects, as for instance, woven fabric pockets for cartridge-belts or carriers, in which sharp-pointed cartridges are carried, and the object is to strengthen and reinforce such a pocket by effective means which will not interfere with the smoothness of the interior of the pocket and which will not be difficult to manufacture.

With the above object in view, the invention consists in the novel features of construction hereinafter fully described, particularly pointed out in the claims, and clearly illustrated by the accompanying drawings, in which—

Figure 1 is a perspective view of a pocket constructed in accordance with my invention, the same being broken away to show one of the reinforcing strips: Fig. 2, a similar view of the reverse side of the pocket, showing the reinforcing strips before being completely inserted: Fig. 3, a longitudinal section through the pocket: Fig. 4, a perspective view of one of the reinforcing strips showing the shape assumed when in position in the pocket: Fig. 5, a similar view of the strip before insertion: Fig. 6, a front view, partly in section, showing a modified form of my invention: Fig. 7, a longitudinal sectional view thereof: Fig. 8, a sectional view of the bottom portion of the pocket, shown in Figs. 6 and 7, showing the receptacles for the reinforcing-strips before being closed by stitching or otherwise: Fig. 9, a view of the reinforcing-strips used with this form: Fig. 10, a rear view of another modified form of my invention, partly in section: Fig. 11, a longitudinal sectional view of this form of pocket, and Fig. 12, a sectional view of the bottom of the same before closing the receptacles for the reinforcing medium.

Pockets of woven fabric of the character referred to have heretofore been reinforced by means applied to the exterior thereof, 55 the reinforcing means consisting of extra

layers of fabric woven therein, or inserted, or wire gauze and other substances secured in place by stitching and the like. The reinforcement by weaving is the best of these forms, as all the others present a certain 60 degree of clumsiness and very great difficulty in manufacture.

My invention consists in reinforcing the pocket by means applied to the exterior thereof, thus enabling me to obtain perfect 65 shapeliness of the pocket and ease in manufacture, and a superior reinforcement, and at the same time one which leaves the inner surface of the pocket absolutely smooth and without projecting edges of cloth, wire or 70 other substances which may be abrasive or obstructive.

In the form shown in Figs. 1, 2 and 3, I weave along the bottom portion of the pocket, upon the exterior thereof, both 75 front and back, an extra ply of fabric, binding it to the main pocket-fabric 1 at regular intervals to form a series of flattened receptacles or tubes 2 which extend from a point on the front of the pocket around underneath and upward on the back thereof. This extra ply is interwoven at its upper 80 edge with the fabric of the pocket on one side thereof, preferably the front side, so that the ends of the tubes are closed on that 85 side. The opposite ends of the tubes are not so closed so that there may be inserted therein, small flexible strips 3, which by reason of their flexibility may be pushed around under the bottom of the pocket and 90 upward on the other side until they reach the closed ends of the tubes. The open ends of the tubes may then be closed by a line of stitching, and the reinforcing-strips held securely in place. The pocket is thus greatly 95 strengthened without in the least marring the smooth contour of its inner surface. My invention enables me to give a perfect shape to the bottom of the pocket, and this shape may be altered by the use of a greater or less 100 number of reinforcing-strips:

In the form shown in Figs. 6, 7 and 8, the tubes 4 instead of being continuous from one side of the pocket to the other, extend only from a line midway on the bottom of 105 the pocket to the front or to the rear side thereof. That is, they are closed at the bottom and are open only at the top, both front and back. This enables me to use for reinforcing purposes, small strips 5 of re- 110

inforcing material which may or may not be flexible. In the first form described, the strips must be of sufficient flexibility to be bent in substantially U-form, while in the 5 second form, they are simply straight strips which need not be susceptible of any bend unless so desired. I insert these straight strips of proper length in the separate tubes formed front and back and meeting at the 10 bottom, and then close the open ends of the tubes by stitching or otherwise as in the first form.

In the form shown in Figs. 10, 11 and 12, the extra ply of fabric is not interwoven 15 with the pocket-fabric at intervals to form tubes, but is interwoven therewith only at the sides thereof, thus forming two pockets or receptacles 6 on the exterior of said pocket as shown in Figs. 11 and 12. This enables 20 me to insert a reinforcing substance 7, as for instance, wire gauze, approximately of the full width of the pocket. If the extra 25 ply is interwoven at the bottom of the pocket with the fabric of the latter as shown in Figs. 11 and 12, two pockets 6 are formed, requiring two pieces of reinforcing material 7, the open ends of said pockets 6 being then closed by stitching or otherwise. The extra 30 ply may, however, be interwoven at one edge with the fabric of the pocket, as shown in Fig. 10, in which event, a single pocket would be formed extending on both sides of the pocket to be reinforced and around the

bottom thereof, thus requiring but a single strip of reinforcing-material 7.

I do not limit my invention to the formation of the tubes or the pockets 6 by inter-weaving an extra ply of material, as such tubes or pockets 6 might be formed of a separate piece of material stitched or otherwise secured to the pocket to be reinforced.

Having thus fully described my invention, what I claim as new and desire to secure by Letters Patent of the United States, is:

1. A woven fabric receptacle having a 45 plurality of tubes formed in the process of weaving, and strips of reinforcing material inserted in said tubes.

2. A fabric pocket having upon its exterior at its lower portion, a plurality of tubes 50 of flexible material, and strips of reinforcing-material inserted and secured in said tubes.

3. A fabric pocket having upon its exterior at its lower portion, a plurality of 55 tubes of flexible material extending from one face of the pocket around beneath the same to the other face thereof, and strips of reinforcing-material inserted and secured in said tubes.

In testimony whereof I affix my signature in the presence of two witnesses.

FRANK R. BATCHELDER.
